(57) **CLAIM**

The ornamental design for a shower curtain, as shown and described.

DESCRIPTION

FIG. 1 is a perspective view of a shower curtain, showing our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an enlarged view of a circle labeled 8 in FIG. 3 of the shower curtain.

The broken lines depict portions of the article that form no part of the claimed design.
